UNITED STATES PATENT OFFICE

GEORGE A. SHAW, OF DAYTON, OHIO.

CLOTHES-LIFTER.

No. 874,547.

Specification of Letters Patent.

Patented Dec. 24, 1907.

Application filed June 14, 1907. Serial No. 378,944.

To all whom it may concern:

Be it known that I, GEORGE A. SHAW, a citizen of the United States, residing at Dayton, in the county of Montgomery and State of Ohio, have invented certain new and useful Improvements in Clothes-Lifters; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 This invention relates to improvements in lifters and may be otherwise termed a "clothes lifter."

The object of the invention is to provide a lifter for removing laundry from boilers. 20 The implement is also adapted to a variety of other uses, for example, in dyeing establishments where fabrics are immersed in receptacles containing the dye-stuff, etc.

In the drawings—Figure 1, represents a 25 view of the lifter showing the two gripping members in their normal position. Fig. 2, is a view at right angles to Fig. 1. Fig. 3, is an end view of the head with parts broken away. Fig. 4, is a detail view of the 30 inner side of one of the arms or gripping members adjacent to the head.

In a detail description of the invention, similar reference characters indicate corresponding parts.

35 The arms or gripping members 1 have their gripping ends 2 curved inwardly and provided with flat engaging surfaces which owing to their construction do not pierce or otherwise mutilate the fabrics. These gripping arms or members are preferably constructed of wood, such material being least affected by the liquids or chemicals in which the lifter is inserted in handling the fabrics; 40 wood is otherwise preferable, owing to its being lighter than metal. The ends of these gripping arms or members 1 terminate in heads 1^a of greater width or thickness than the gripping ends 2, the entire length of said members being tapered from these heads to 45 the gripping ends. Attached to the outer sides of the head portions of the said members, is a plate spring 4 which extends in a substantially semi-circular head 5 which lies

beyond the ends 3 of the heads. This outer spring provides a hand portion by which the 55 implement is manipulated, and in addition thereto it provides the necessary resiliency to assist in maintaining the gripping members normally separated. This plate spring 4 so curved is of a width equal to that of the 60 gripping member or arms 1 throughout its length.

7 designates an inner plate spring secured to the inner sides of the head portions of the gripping arms or members 1, and extending 65 from one arm to the other in a convolute or head 6 which lies beyond the ends of the gripping members. This inner plate spring 7 is also of the same width as the gripping arms or members, and together with the 70 head 5 of the outer spring forms a substantial attachment uniting the ends of the gripping arms. The head or convolute 6 of the inner spring contacts with the inner side of the head 5 of the outer spring and is rigidly 75 attached thereto by a rivet 8 which maintains said spring in rigid connection.

9 designates a slotted guide plate secured to one side of the inner spring and the adjacent gripping member. This plate has an 80 elongated slot 10 which penetrates a slot 14 in the other side of the inner spring and a slot 13 in the adjacent gripping member, said end so projected in said slots being maintained therein by a pin 11 inserted in 85 the gripping member across the opening 13. This pin 11 engages the end of the slot 10 and maintains the gripping arms or members normally in the position shown in Fig. 1. The guide plate 9 also provides a substantial 90 means for preventing the gripping members or arms from having any lateral or side movements and insures the two arms moving always in alignment in manipulating the device. 95

I claim:

A clothes lifter comprising two gripping arms with inturned engaging ends, an outer leaf spring attached to the outer sides of said arms and uniting the same by extending 100 from one arm to the other in the form of a bow, an inner leaf spring united to the inner sides of said arms and extending from one arm to the other in the form of a bow, said outer and inner springs being rigidly united 105 beyond the ends of the arms, and the width

of said springs being equal to the widths of the arms, a slotted plate having one end attached to the inner leaf spring and the other end penetrating a slot in the other side of the 5 inner leaf spring and in the arm, and a pin penetrating the slot in the arm and the slot in said plate and providing means to limit the spreading movement of the arms under

the combined action of the two springs, as herein shown and described.

In testimony whereof I affix my signature, 10 in presence of two witnesses.

GEORGE A. SHAW.
